CLAIM

The ornamental design for a cover for a paint roller pan, as shown and described.

DESCRIPTION

FIG. 1 is a perspective view illustrating my new design in use;

FIG. 2 is a top plan view thereof;

FIG. 3 is a bottom plan view thereof;

FIG. 4 is a right side view thereof;

FIG. 5 is a left side view thereof;

FIG. 6 is a front view thereof; and,

FIG. 7 is a rear view thereof.

The broken lines in FIG. 1 are for information only, and form no part of the instant design.
